UNITED STATES PATENT OFFICE.

JOSEPH S. POWER AND JOHN W. PEARSON, OF DAYTON, OHIO, ASSIGNEES TO THE
DAVIS SEWING MACHINE COMPANY, OF DAYTON, OHIO, A CORPORATION OF DELA-
WARE.

LOCKING MECHANISM.

Application filed March 28, 1921. Serial No. 456,164.

To all whom it may concern:

Be it known that we, JOSEPH S. POWER and JOHN W. PEARSON, citizens of the United States, residing at Dayton, in the 5 county of Montgomery and State of Ohio, have invented certain new and useful Improvements in Locking Mechanism, of which the following is a specification, reference being had therein to the accompanying drawing.

Our invention relates to a locking mechanism for a control wire and in particular to a locking mechanism for controlling the operation of a drain.

15 The object of our invention is to provide a positive and simple means of positioning a Bowden wire with respect to its casing and keeping it in locked position until actuated by the operator. In the particular 20 adaptation shown we have attached it to a drain described and claimed in our co-pending application No. 456,163. It is our purpose to provide a structure that will be positive in action, simple to operate by unskilled 25 users, and will be cheap to construct.

Referring to the drawings:

Fig. 1, shows the locking mechanism mounted on one wall of a washing machine or a washing machine tub with a view of 30 the drain to be operated shown in section;

Fig. 2, is a plan view of one of the locking arms;

Fig. 3, is a plan view of the spring retaining clamp with the spring members, 35 Bowden wire and Bowden wire tube in section; and,

Fig. 4, is a section through *a—a* of Figure 1, in the direction of the arrows and shows the position of the spring ends.

40 Discussing the drawings in detail, 1 is a finger piece or operating head that is connected to the Bowden wire 2 by a set screw 3. This head has a tubular casing 4 loosely fitting over the top of the Bowden wire 45 guide 5. At the lower end of this tubular casing 4 is an expanded portion or collar 6 having a groove 7 therein. This groove is embraced on either side by the semi-circular end 8 of the locking arm 9. The outer end 50 of the locking arm has an aperture 10 that fits over the hooked end 11 of the spring wire 12. This spring wire 12 resists expansion and tends to keep the arms 9 from passing over the dead center. This wire 55 is U-shaped and is supported at 13 by the

clamp 14 which also serves as a guide at 15 for the casing 5 of the Bowden wire control. This casing is further retained in position by the clamp 16. The ends 22 of the spring wire 12 are so shaped as to form 60 a stop, in the open position, for the collar 6.

The Bowden wire may pass to any desired location. In this instance it is operating the valve member 17 in connection with a lip 18 of the orifice 19 of the drain 20 which is 65 attached to a washing machine tub 21. The locking structure may be attached through the clamps 14 and 16 to any desired portion of the washing machine. In this instance I have shown it attached to the side of the 70 tub 21.

To operate the lock, the operator grasps the head 1 to which the Bowden wire 2 is connected and pushes it upwardly or downwardly. It will remain in either position 75 because of the action of the spring 12 which resists the arms 9 passing over the dead center because that is the point of the maximum expansion of the two arms of the spring 12 and the tendency of the spring 80 arm is to maintain the head 1 and the tubular member 4 together with the collar 6 in either the upper or lower position and to maintain them in that position positively.

While we have shown and described cer- 85 tain features as constituting my invention, it will be understood that parts have been shown for purposes of illustration only, and that we do not desire to be limited to such details, as obvious modifications will occur 90 to a person skilled in the art.

Having thus fully described our invention, what we claim as new and desire to secure by Letters Patent, is:—

1. In combination, a Bowden wire, a casing 95 for said wire, an actuator head attached to said wire and slidably engaging with one end of said casing, a collar on said actuator head, an arm having one end engaging said collar and the other end engaging a resilient 100 means to resist the outward movement of the arm, and means for maintaining the guiding means for the Bowden wire in a fixed position, whereby the Bowden wire 105 may be maintained in desired positions.

2. In combination, a Bowden wire, a tubular member for guiding said wire, an actuator member attached to said wire with a cylindrical portion fitting over the guiding member for the wire, a collar on one end of 110

said cylindrical portion surrounding said guiding member, a pair of arms having their ends engaging with a groove in said collar, a U-shaped spring member having arms on either side of said collar, the ends thereof engaging with the free ends of the arms, whereby the wire may be maintained in any desired position.

3. In combination, a Bowden wire, a tubular member for guiding said wire, an actuator member attached to said wire with a cylindrical portion fitting over the guiding member for the wire, a collar on one end of said cylindrical portion surrounding said guiding member, a pair of arms having their ends engaging with a groove in said collar, a U-shaped spring member having arms on either side of said collar, the ends thereof engaging with the free ends of the arms, a clamp for supporting said casing of the wire and the U-shaped resilient member in position, and a clamp for maintaining the upper end of the casing in position adjacent the upper ends of the resilient members, whereby the wire may be maintained in any desired position.

4. In combination, a Bowden wire, a tubular member for guiding said wire, an actuator member attached to said wire with a cylindrical portion fitting over the guiding member for the wire, a collar on one end of said cylindrical portion surrounding said guiding member, a pair of arms having their ends engaging with a groove in said collar, a U-shaped spring member having arms on either side of said collar, the ends thereof engaging with the free ends of the arms, a clamp for supporting said casing of the wire and the U-shaped resilient member in position, and a clamp for maintaining the upper end of the casing in position adjacent

the upper ends of the resilient members, and means to limit the upward movement of the collar, whereby the wire may be maintained in any desired position.

45

5. In combination, a Bowden wire, a casing for said wire, an actuator head attached to said wire and slidingly engaging with one end of said casing, a collar on said actuator head, an arm having one end engaging said collar and the other end engaging a resilient means to resist the outward movement of the arm, means for maintaining the guiding means for the Bowden wire in a fixed position, a valve member attached to said wire, a valve port, and a yielding seat for said valve port to cooperate with said valve member, whereby the Bowden wire may be maintained in desired positions.

50

6. In combination, a Bowden wire, a casing for said wire, an actuator head attached to said wire and slidingly engaging with one end of said casing, a collar on said actuator head, an arm having one end engaging said collar and the other end engaging a resilient means to resist the outward movement of the arm, means for maintaining the guiding means for the Bowden wire in a fixed position, a valve member attached to said wire, a valve port, and a yielding seat for said valve port to cooperate with said valve member, said casing for the Bowden wire attached to said valve member being projected into said valve member and slidingly engaging therewith to act as a guide therefor in positioning said member with respect to said valve seat, whereby the Bowden wire may be maintained in desired positions.

55

In testimony whereof, we affix our signatures.

JOSEPH S. POWER.
JOHN W. PEARSON.
